PARCEL POSTAGE CALCULATING, PRINTING, AND METERING MACHINE

William J. Pearson, Los Angeles, Calif., and Thomas I. Brown, deceased, late of Los Angeles, Calif., by William J. Pearson, Los Angeles, Calif., administrator, assignors, by mesne assignments, to Postal Automatic Machines, Inc., a corporation of Delaware

Original applications May 16, 1931, Serial No. 537,975, and April 3, 1937, Serial No. 134,872. Divided and this application April 8, 1939, Serial No. 266,900.

4 Claims. (Cl. 101—100)

This invention relates to postage metering machines for printing parcel postage stamps and more particularly to a mechanism for guarding printing type and locking unit when the latter is removed from the machine. This application is a division of our previous applications, Serial No. 537,975, filed May 16, 1931, and Serial No. 134,872, filed April 3, 1937, both of which relate to parcel post metering and printing machines.

In the postal system of the United States, great quantities of mail matter are handled daily, the postage on all of which was until recent years paid by purchase of engraved stamps which were applied to the letters or packages to be mailed and then cancelled by the post office at the point of origin. A few years ago a new method of selling postage for use on letters was developed in which method the mailer purchases or leases from the manufacturer, a machine which is authorized for use by the Post Office Department, and which is adapted to print stamps directly on envelopes, the amount of postage thus printed being registered in the machine by mechanism which stops and locks the machine when a prepaid quantity is exhausted. When thus locked, each machine, or the register thereof, as the case may be, must be taken to the post office and reset for printing another quantity of postage which is paid for at the time by the mailer.

In parcel post metering machines developed to date, it has been necessary to return the entire machine to the post office to have it reset after a given purchase of postage has become exhausted. The printing and metering unit, being of relatively small bulk and weight, is easily removable from the machine so that the purchase of further postage from the post office may be accomplished by presentation of this unit to the postal authorities for resetting. The printing and metering unit has novel means whereby it is automatically locked against being tampered with when removed from the machine.

It is an object of our invention to provide novel means for guarding the printing and serial type from fraudulent use when the meter is removed from the machine.

It is a further object of our invention to mount the guarding means coaxially with the type of the unit.

An additional object is to provide means for locking the unit to the base when it is positioned in the machine.

A still further object is to remove the shield from type guarding position when the unit is locked in position in the machine.

Various other objects and advantages will be apparent from the following description of the accompanying drawings, which form a part of this disclosure and which illustrate a preferred form of embodiment of the invention.

The manner of accomplishing the foregoing objects, as well as further objects and advantages, will be made manifest in the following description, together with the accompanying drawings, in which:

Figure 1 is a longitudinal cross sectional view of a parcel postage calculating, printing and registering machine.

Figure 2 is an enlarged detail sectional view of the printing and registering unit.

Figure 3 is a cross sectional view taken on the line 3—3 of Figure 2.

Figure 4 is a fragmentary view illustrating the means for guarding the printing press of our invention against fraudulent use, such means being incorporated in the machine as shown in the right hand portion of Figure 2.

Figure 5 is a fragmentary vertical sectional detail view taken on the line 5—5 of Figure 3, illustrating the serial number of our invention.

Figure 6 is a vertical sectional view taken on the line 6—6 of Figure 2, illustrating certain control features associated with the removable printing and registering unit of our invention.

Figure 7 is a fragmentary perspective view illustrating the manner of mounting and locking the removable printing and registering unit in place.

Figure 8 is a longitudinal cross sectional view of the parcel postage calculating, printing and metering machine showing the relative positioning of the printing and metering unit.

In the present disclosure, only enough of the parcel post machine 60 has been shown to indicate the association of the invention with this machine. The printing and metering unit 65 is mounted on a supporting frame 232 secured to a base plate 261 snugly received in a shallow recess 260 in the upper surface of the base 61 of the machine 60. The frame 232 includes the standards 263 and 264 connected together by spacer bars 265, 266 and 267 (Figures 6 and 7). In the bars 265 and 266 are uniformly spaced pairs of annular grooves 268; in the bar 267 are a pair of annular grooves 269 which are spaced apart a shorter distance than the grooves 268 (see Figure 6).

The standards 263 and 264 are provided with pairs of bearings 270, 271 and 272 (see Figures 1 and 8), the purpose of which will be made evident hereafter.

Provided in the deck 176 of the housing 171 is an opening 275 through which the removable printing and metering unit 65 is adapted to be lowered so as to rest upon the supporting frame 262.

The removable printing and metering unit 65 has a casing 276 comprising side plates 277 and 278 connected together and rigidly spaced by rods 279, 280 and 281 (Figure 2). The side plates 277 and 278 have their lower portions 282 and 283 offset inwardly as clearly shown in Figures 2 and 3.

The side plates 277 and 278 are provided with pairs of jaws 285, 286 and 287, the latter pair being formed on the lower side plate portions 282 and 283. When the unit 65 is lowered into its proper position on its supporting frame 262, the pairs of jaws 285 and 286 extend into the grooves 268 in the cross bars 265 and 266 as shown in Figure 2, while the jaws 287 extend into the grooves 269 in the bar 267.

The casing 276 has a cover plate 290 secured in any desired manner on the upper edges of the side plates 277 and 278. The cover plate 290 is provided with lugs 291 in which is mounted a bail 292 for handling the unit 65. This plate has a window 293, preferably covered with glass to exclude dust from the unit and yet permit observation of the ascending register 78 of the unit. Hingedly mounted in a suitable opening in the cover plate 290 is a door 294 having a sunken window 295 preferably covered with glass to exclude dirt from the unit but permit observation of the descending register 77. Mounted in the door 294 adjacent its free edge is a key lock 298 having a swingable sealing plate 299 for sealing the lock.

A further element of the casing 276 is a sheet metal member 304 which is bent to conform to the edges of the side plates 277 and 278 and is permanently secured to these edges so as to form a front wall 305, a bottom wall 306 and a rear wall 307. The sheet metal member 304 is formed as shown in Figure 2 to leave the jaws 285, 286 and 287 exposed. The front wall 305 has six vertical slots 310 formed therein, the rear wall 307 has two slots 311 formed therein, and the bottom wall 306 has an opening 312 formed therein, the purpose of these openings being made evident hereinafter.

A serial number printer is also illustrated (Figures 3 and 5), and includes three printing wheels 480, 481 and 482, mounted on the printing mechanism shaft 320 between the wing 318 of the block 315 and the printing wheel 330 of the computer responsive printing mechanism 76. This mechanism is adapted to be guarded at the time the printing type is concealed, as will be explained later in more detail.

The mechanism for guarding the printing type and locking unit when the latter is removed from the machine is generally indicated at 81. This mechanism (best shown in Figures 2, 3, 5, 6, 7 and 8) includes a key lock 530 mounted in the side plate 278 of the unit 65, and a gear 531 which is locked against rotation excepting when a key 532 (Figure 6) is inserted into the lock, whereupon rotation of the key is adapted to turn the gear.

The key 532 is secured upon the end of a rod 533 having a head 534, and is supported in a sleeve 535 mounted in a frame 536 which is secured to an extension 537 of the standard 264. Disposed between the frame 536 and the head 534 is a spring 540 which holds the key 532 nor-

mally retracted in a forward extension 541 of the sleeve 535. When the unit 65 is properly placed in the machine 60, the key is disposed opposite the lock 530 so that the head 534 may be engaged manually to insert the key 532 in the lock and rotate the gear 531. Journalled at its opposite ends in the unit side plates 277 and 278 is a rocker shaft 545 having rockers 546 rigidly secured thereto; these rockers are provided with locking lugs 547 which, when the shaft 545 is rotated, extend outwardly through the openings 311 in the wall 307 of the unit 65 to a position (shown in full lines in Figure 2 and in broken lines in Figure 4) just beneath the spacer bar 266 so as to effectively retain the unit 65 in the machine 60.

Pivotedly mounted on a standard 549 on the plate 278 is a gear 550 which meshes with the gear 531 and has an arm 551 which is pivotally connected by a link 552 to one of the rockers 546. The rockers 546 are connected by a bar 553 which has links 554 and 555 pivotally mounted thereon.

Disposed in the lower part of the unit 65 adjacent the opening 312 in the lower wall 306 thereof, is a type guard 560 including an arcuate face plate 561 and guard end walls 562 and 563, these walls being pivoted on the shaft 320 just within the wings 317 and 318 of the printing mounting block 315. Extending upwardly from the guard end wall 562 is an arm 566 which is pivotally connected to the lower end of the link 555.

Extending inwardly from the side plate 278 beneath the shaft 430 is a horizontal stud 567 (Figures 3 and 4), which is supported at its inner end by a vertical standard 568 and on which is pivotally mounted a locking rocker 569 disposed alongside a cam H. The lower end of the rocker 569 is pivotally connected with the link 554. On a face of the cam H, in the same plane as the rocker 569, is a shoulder 570.

In the wall 174 is a removable door 571. At the time that the unit 65 is inserted in the machine, the operator may put his hand through the door opening, grasp the key rod head 534, push the key 532 into the lock 530, and by rotating the head 534, turn the gear 531 (Figure 6).

In the normal position of the mechanism 81 when the unit 65 is out of the machine 60 (shown in full lines in Figure 4), the rockers 546 are swung so that the lugs 547 are retracted; the guard 560 is swung downwardly through the opening 312 to completely guard the type 322 and 483 from fraudulent use; and the locking rocker 569 is swung into the path of the shoulder 570 on the operating cam H so as to prevent rotation of the shaft 461 in the direction of the arrow 465. With the mechanism 81 thus disposed, fraudulent use or operation of the unit 65 in any manner is impossible. When the key 532 is inserted in the lock 530 and the gear 531 is rotated, however, the parts of the mechanism 81 are swung to the broken line position in Figure 4 or the full line position in Figure 2, in which position the lugs 547 come up beneath the spacer bar 266 so as to retain the unit 65 in the machine 60; at the same time the guard 560 is swung away from the front of the printing type and the rocker 569 is swung out of the path of the shoulder 570, thus freeing the shaft 461 to permit its rotation.

It is thus seen that the unit 65 is free to operate only when it is positively retained in the machine 60 by the locking lugs 547.

While we have shown and described but a

single embodiment of our invention, it is to be understood that various changes and modifications might be made in this without departing from the spirit of the invention or the scope of the appended claims.

1. A postage metering device having a base portion, a detachable meter and a printing device, a casing enclosing the printing device, said casing having an opening to expose said printing device to permit printing when said casing is attached to said base, a shield attached to the casing movable to close said opening, means for locking the casing to said base, means for releasing the locking means from effect on the meter casing to enable removal thereof, manually operable locking means to lock said casing at will to said base portion, and means operated by said releasing means to move said shield to cover said opening when said casing is unlocked from said base portion.

2. A postage metering device having a base portion, a detachable meter and printing device, a casing enclosing the printing device, said casing having an opening to expose the type wheels of said printing device to permit printing when said casing is attached to said base, an arcuate shield pivotally supported coaxially with said type wheels to close said opening, means for locking the casing to said base, means for releasing the locking means from effect on the meter casing to enable removal thereof, manually operable locking means to lock said casing at will to said base portion, and means operated by said releasing means to move said shield to cover said opening when said casing is unlocked from said base portion.

3. A postage metering device having a base portion, a detachable meter and a printing de-

vice, a casing enclosing the printing device, said casing having an opening to expose said printing device to permit printing when said casing is attached to said base, a shield attached to the casing movable to close said opening, means for locking the casing to said base including a hook and a link connected thereto to operate the mechanical locking means, means for releasing the locking means from effect on the meter casing to enable removal thereof, manually operable locking means to lock said casing at will to said base portion, and means operated by said releasing means to move said shield to cover said opening when said casing is unlocked from said base portion.

4. A postage metering device having a base portion, a detachable meter and printing device, a casing enclosing the printing device, said casing having an opening to expose the type wheels of said printing device to permit printing when said casing is attached to said base, an arcuate shield pivotally supported coaxially with said type wheels to close said opening, means for locking the casing to said base including a hook and a link connected thereto to operate the mechanical locking means, means for releasing the locking means from effect on the meter casing to enable removal thereof, manually operable locking means to lock said casing at will to said base portion, and means operated by said releasing means to move said shield to cover said opening when said casing is unlocked from said base portion.

WILLIAM J. PEARSON,
WILLIAM J. PEARSON,
*Special Administrator of the Estate of Thomas I.
Brown, deceased.*
